UNITED STATES PATENT OFFICE.

JAMES TIMMS, OF COLUMBUS, OHIO.

CAR-COUPING.

SPECIFICATION forming part of Letters Patent No. 417,347, dated December 17, 1889.

Application filed January 19, 1889. Serial No. 296,830. (No model.)

To all whom it may concern:

Be it known that I, JAMES TIMMS, of Columbus, in the county of Franklin and State of Ohio, have invented certain new and useful 5 Improvements in Car-Couplers, of which the following is a specification, reference being had to the accompanying drawings.

My improvements relate to what are known as "vertical hook-couplers;" and their object 10 is to improve that class of couplers in the particulars hereinafter pointed out.

My invention relates to the provision of proper buffing-surfaces for the knuckle, in connection with a tapering coiled spring and 15 a loose-knuckle pivot-pin, whereby perfect action of the knuckle under all circumstances and security against breaking are provided for.

My invention also relates to improvements 20 in bumpers for a draw-head of a coupler of the type mentioned.

In the accompanying drawings, Figure 1 is a horizontal central section of a draw-head, showing the knuckle in plan. Fig. 2 is a 25 side view of a bumper detached, showing the rubber cushion in section. Fig. 3 is a similar view of a shorter bumper adapted to be applied to the rear part of the draw-head. Fig. 4 is a cross-section of the draw-head, 30 showing the relation of a gravity-catch with respect to the knuckle. Fig. 5 is a view of a bumper in position as it would be applied to the sill or frame-work of a car. Fig. 6 is a section on line 6 6 of Fig. 1, showing the 35 stepped bearings of the knuckle in the draw-head. Fig. 7 is a diagrammatical view of a draw-head, showing the pivot-pin hole and pin to be in line with the inner striking-face of the draw-head.

40 Referring to the letters upon the drawings, A indicates a draw-bar; B, the draw-head; C, the knuckle, pivoted at D approximately on a line with the inner striking-face E of the draw-head. This location of the pin is 45 desirable for security, and also so that the buffing strain or blows in service shall be the least likely to do injury to the pin.

F indicates the guard-arm of the draw-head, and G a gravity-catch or knuckle-fastening 50 bolt, with a sliding bearing G' in the draw-head.

X indicates a lateral extension of the knuckle, adapted to engage with the catch G, as shown in Fig. 1.

Referring now particularly to what constitutes my improvements, H indicates a cone-shaped coiled spring, which I introduce between the draw-head and the knuckle in such relation to these parts that it tends to help uncouple when the fastening-bolt G is 60 withdrawn from the fastening position.

I indicates a socket in the draw-head for seating the base of the coiled spring, and I' another socket in the knuckle for receiving the pointed end or top of the spring. By 65 making the spring tapered I am enabled to get it into the position shown, where a much shorter spring than heretofore used will answer the purpose. In this way the spring takes up but little room and metal is saved 70 in the construction of the knuckle. The spring, being short and with a broad base resting in sockets at each end, is not liable to tilt to one side or get out of place when in the form and position shown. In action it is compressed 75 and extends in a straight line and does not catch and bind as a curved coiled spring is liable to do. It is located so as to act on a line substantially tangential to the surface of the knuckle on which it bears. As it touches 80 the knuckle only at its end and operates in a straight line, it is more reliable and efficient in action than a curved spring, and, being tapered, as described, it can be set and operated in the manner and position shown, so 85 as to work to the best advantage.

K indicates a shoulder, and L another shoulder upon the knuckle K', and K² and K³ indicate corresponding bearings on the draw-head. These shoulders are formed on each 90 side of the knuckle alike, and they form a stepped seating of the knuckle in the draw-head which is very strong. The shoulders and bearings being concentric with the pivotal center of motion of the knuckle, and the 95 pivot-pin of the knuckle being slightly loose in its fitting in the pin-hole, all the dangerous buffing strains and blows of service are taken up by the draw-head substantially in line with its axis, so that the pivot-pin of the 100 knuckle is not likely to suffer injurious strain, and there is no such lateral strain upon the

draw-head as to be liable to break it. Besides this protection to the pivot-pin, it is located, as shown, far back substantially on a line with the inner face of the draw-head, which brings it through about the center of the greatest body of metal surrounding it both in the draw-head and the knuckle and secures great strength of bearings. In couplers of this class it is desirable that the shocks of 10 blows shall be diminished as much as possible by the action of springs or cushions. The coupling mechanism must always bear the shocks or blows up to the point where the force is sufficient to operate the draw-bar springs. Beyond this, a shock is sometimes experienced when the draw-bar springs have yielded to the maximum extent and the draw-head comes in contact with the draft timber or beams of the car. In order to protect the 15 coupler from such blows and shocks, I employ an improved cushion or bumper upon the guard-arm of the draw-head, both in front and rear, somewhat upon the general principle of United States Patents Nos. 328,547 and 20 341,292.

I provide a bumper-chamber M in the guard-arm in front, and I may also provide a chamber M' in the rear of the draw-head. This chamber is divided into three parts, a being 25 for the bumper N, b the enlarged part for the rubber cushion O, and c to receive the end of the headed bolt P when the cushion is compressed. Q indicates a washer seated in the cushion, and through which the headed bolt P passes. The bolt serves to secure the bumper and cushion together. I form this cushion by the combination of the bumper, the bolt, the 30 rubber cushion, and the washer, so that I can 35 insert it into a properly-formed opening. The enlarged part of the cushion entering the enlarged part of the opening, the device will stay in place and be ready for service. In Fig. 5 I have shown the application of this bumper mechanism to the draft-timber of a car instead of in the rear part of the guard-arm of the draw-head, in which position it 40 would serve the same purpose; but I prefer to apply it on the guard-arm.

45 50 What I claim as new is—

1. The combination, with a draw-head provided with a guard-arm, a socket or seat, and a knuckle pivoted to the draw-head and pro-

vided with a corresponding socket or seat, of a conical coiled spring located in front of the 55 guard-arm, with its larger end resting in the socket or seat of the draw-head and its smaller end in the socket or seat of the knuckle, and a latch for engaging the inner end of the knuckle.

60 2. The combination of the concentric shoulders K and L upon the draw-head B and the corresponding concentric bearings K' and K' upon the draw-head, the tapering coiled spring H, and the knuckle pivot-pin C, located in line with the inner face of the draw-head, substantially as set forth.

3. An improved buffering device for a draw-head of a car, consisting of the bumper N, the cushion O, the washer Q, and the bolt P, for securing them together, substantially as set forth.

4. A draw-head provided with a bumper-chamber divided into three parts—a for the bumper, b an enlarged part for a rubber cushion, and c a small part to receive a bumper-bolt—substantially as set forth.

5. In an automatic car-coupler, the combination, with a draw-head and an integral guard-arm provided with a transverse inclined recess therein, of a knuckle pivoted to the draw-head and a gravity-catch located in the recess in the guard-arm to engage the knuckle, substantially as set forth.

6. In an automatic car-coupler, the combination, with a draw-head and an integral guard-arm provided with a transverse inclined recess therein, of a knuckle pivoted to the draw-head and having a lateral extension and a gravity-catch located in the recess in the guard-arm and adapted to engage the lateral extension of the knuckle, substantially as set forth.

7. In an automatic car-coupler, the combination, with a draw-head and an integral guard-arm having an inclined recess therein, of a knuckle pivoted to the draw-head, a gravity-catch in the recess in the guard arm to engage said knuckle, and buffers on said guard-arm, substantially as set forth.

100 In testimony of all which I have hereunto subscribed my name.

JAMES TIMMS.
